CRACKING AND EXTRACTING HYDROCARBON OILS WITH A SELECTIVE SOLVENT

Edward F. English, Baton Rouge, La., assignor to Standard Oil Development Company, a corporation of Delaware

Application November 21, 1934, Serial No. 754,026

1 Claim. (Cl. 196—50)

This invention relates to a process of treating hydrocarbon oils, such as the various mineral oils including petroleum oils, shale oils, oils obtained in the low temperature carbonization of coal, hydrogenated oily products, etc. by the combination of a cracking and a solvent extraction process, and will be fully understood from the following description when read in conjunction with the drawing, the sole figure of 10 which is a diagrammatic side elevation partly in section of an apparatus appropriate for carrying out the invention.

The main object of the present invention is to subject the hydrocarbon oil to a cracking process, to separate a cycle stock from the cracked products, this cycle stock being a distillate product boiling higher than the naphtha obtained in the cracking process, to subject this cycle stock to a treatment with a selective solvent for separation thereof into a more paraffinic and a less paraffinic product, and to subject these two products to different kinds of treatments.

Referring now to Fig. 1, the same will be described in conjunction with the method of operating the apparatus illustrated. The fresh feed, such as for example, gas oil, is pumped from storage tank 1 through partial condenser 2 and heat exchangers 3 and 4 into the accumulator 5. The raffinate from the solvent extraction step 20 is also passed into the accumulator, as will be described hereinafter. The mixed feed from the accumulator is fed through high pressure intercondenser 6 and heating coil 7 into the soaking drum or reaction chamber 8. The mixed feed is heated to the cracking temperature in coil 7 and undergoes the desired extent of cracking in the soaking drum 8. A limited amount of cracking usually takes place in the heating coil. If desired, the soaking drum may be omitted 30 from the circuit, the coil temperature being raised to increase cracking in the heating coil and compensates for loss of cracking in the soaking drum. The cracked effluent from 8, after partial release of the pressure, is discharged into 40 the separator 9 which may be provided with various fractionating devices, such as discs and doughnuts. Tar is withdrawn from the separator through cooler 10 into a storage tank (not shown). Vapors from the separator pass 50 through the high pressure intercondenser 6 and, through heat exchangers 3 and 4 into the lower part of a bubble tower 11. Part of a heavy cycle stock condensed in intercondenser 6 and/or part of the cycle stock from heat exchangers 3 and 4 55 may either be returned to the separator 9 or

withdrawn from the unit through cooler 12 or passed to a solvent extraction unit. The bubble tower 11 is provided with efficient fractionating means, such as bubble cap plates, and serves for the separation of the naphtha with the desired endpoint as overhead product. The naphtha vapors are passed through the partial condenser 2 and final condenser 15, into the receivers 16—16a, provided with vents for the release of gases through lines 17 and 18. Part of the naphtha is 10 returned to the top of the bubble tower 11 through line 17a as a reflux for the control of the fractionation. The liquid product obtained at the bottom of the bubble tower 11 is a cycle stock which is run through heat exchanger 19 15 and cooler 19a into the mixing tank 14 of the extraction unit. As cooling medium in cooler 19a water or chilled brine or other suitable cooling medium may be used to reduce the temperature of the cycle stock from bubble tower 11 to be- 20 low that at which cycle stock and solvent are completely miscible. The temperature at which extraction is carried out is selected to give the desired character of extract and/or raffinate. The selective solvent from storage tank 20 is 25 passed to the mixer 14 and thoroughly admixed with the cycle stocks, after which the mixture is forwarded to the settling tank 21 in which separation into two layers, viz, raffinate layer and extract layer takes place. The so-called 30 raffinate layer consisting of the more paraffinic constituents of the cycle stock together with some dissolved solvent, is reheated in reboiler section 22 arranged in the same furnace as heating coil 7, and then discharged into the strip- 35 ping tower 23 on which a vacuum is preferably maintained. The selective solvent is obtained as overhead vapor condensed in condenser 24 and returned to the selective solvent tank 20. The solvent-free raffinate is then passed to the ac- 40 cumulator 5 for reocracking. Alternatively, all or part of the raffinate may be removed from the system through line 25 into a storage tank (not shown) and used for the manufacture of Diesel oil, heating oil or similar products. The ex- 45 tract layer which consists of the selective solvent and non-paraffinic constituents extracted from the cycle stock is reheated in heat exchanger 19 and then passed through the release valve 26 to tower 27. In this tower the selective sol- 50 vent is taken overhead, condensed in condenser 28 and returned to the mixer 14 or storage tank 20. If the desired temperature of extraction is below that obtainable by water cooling, other suitable cooling medium may be used in an 55

auxiliary cooler subsequent to condenser 28 to further cool solvent before return to mixer 14. The extract removed as bottoms from tower 27 is introduced into the vacuum stripper 29 in which the remainder of the selective solvent is removed as overhead product condensed in condenser 30 and returned to the storage tank 20. The extract is removed from the bottom of the stripper 29, cooled in cooler 31 and then passed to a storage tank 34 for various uses to be explained further below. Alternatively, the extract may be subjected to cracking under conditions different from those used in the cracking of the mixed feed. Other methods of utilizing the extract are shown diagrammatically and consist of either submitting the same to hydrogenation in the hydrogenation unit 35 or to a chemical treatment in the chemical treating unit 36.

20 Referring to Figure 2, fresh feed is withdrawn from tank 50 by means of pump 51 and forced through heating coil 52 in furnace 53. The heated oil is then passed through line 54 into a separator 55 from which the heavy tarry products are withdrawn through line 56. The vapors from separator 55 are withdrawn through line 57 and introduced into a fractionating tower 58, from which gasoline vapors are removed through line 59, passed through a cooler 60 and thence passed through line 61 into a gasoline storage tank 62. The heaviest fractions in tower 58 are withdrawn through line 63. An intermediate fraction or cycle oil is withdrawn from tower 58 through line 64 and introduced into a counter-current extraction tower 65. A suitable selective solvent contained in storage tank 66 is withdrawn by means of pump 67 and forced through line 68 into the top of tower 65. Raffinate is removed from tower 65 through line 69 and introduced into a still 70 in which the hydrocarbons are distilled from the solvent in the event that the solvent used is higher boiling than the hydrocarbon fractions. It will be understood that if the solvent used is lower boiling than the hydrocarbons, the solvent will be distilled from the hydrocarbons in still 70. The hydrocarbon vapors are removed from still 70 through line 71 and after passing through a cooler 72, are passed through line 73 into the fresh feed tank 50. The solvent is removed from still 70 through line 74 and returned to the solvent supply tank 66.

55 The extract is removed from tower 65 through line 75 and introduced into a still 76 in which the solvent is separated from the hydrocarbons by distillation. As indicated above, if the solvent is higher boiling than the hydrocarbons, the latter will be vaporized, and if the solvent is lower boiling than the hydrocarbons, the solvent 60 will be vaporized. The hydrocarbon vapors are removed from still 76 through line 77 and collected in extract storage tank 78. The solvent is removed from still 76 through line 79 and returned to the solvent supply tank 66.

65 The extract is withdrawn from tank 78 by pump 80 and passed through line 81 into a second heating coil 82 in furnace 83, wherein the extract is cracked at a higher temperature than the fresh paraffinic feed oil in heating coil 52. The heated oil from coil 82 is passed through line 84 and merges with the heated oil from coil 52 flowing through line 54.

70 The selective solvent may be any of those known to be effective in the separation of a hydrocarbon oil into more paraffinic and less

paraffinic constituents. Usually the extract removed by the selective solvent contains the unsaturated naphthenic and aromatic constituents, while the raffinate consists of the more paraffinic constituents. We may cite phenol, the several 5 cresols, aniline, furfural, nitrobenzene, triphenyl phosphate, triorthocresyl phosphate, liquid sulfur dioxide, etc. as examples of selective solvents which may be used in the carrying out of the present process. Instead of one solvent a mixture of them may be used; for example, a mixture of phenol with cresols. The action of the selective solvent may also be modified by the addition of other organic or inorganic solvents such as, for example, water, alcohols, glycol, etc. 10 The extraction step consists of mixing the cycle stock to be extracted with, say, an equal volume or more of the selective solvent, thoroughly agitating the mixture, then allowing separation of two layers to take place at a temperature below 20 that at which the solvent becomes completely miscible with the oil. The raffinate layer and the extract layer are then separated from each other and the selective solvent is removed from both layers, usually by means of distillation, but other 25 means, either physical or chemical, may also be used.

25 The cracking part of the present process may be carried out in the liquid phase at a pressure of several hundred pounds per square inch, say between 250 and 1,000 pounds per square inch, or even at pressures higher than that, or in the vapor phase at comparatively low pressures approaching atmospheric pressure. The temperature may be any of the usual cracking temperatures or may be considerably higher than say 1,000° F. although, in many cases, it is preferred to carry out the present process at medium temperatures, say between 800-1,000° F. The arrangement described above and illustrated in the 30 drawing is a tube and tank cracking system, but other systems may also be used. Further, the arrangement shown may be modified in various ways; thus, for example, when the fresh feed is a dirty stock, such as a topped crude, it 35 may first be preheated and then fed into the separator 9 instead of into the accumulator 5.

35 The raffinate is usually returned to the cracking system as a cycle stock and fed for this purpose into the accumulator 5. However, part or 40 the whole of the raffinate may be removed and used for various purposes, such as Diesel fuel, heating oil, furnace oil, etc. The extract may be subjected to cracking under conditions different from those used in the main cracking system composed of heating coil 7 and soaking drum 8. It may also be withdrawn and subjected to hydrogenation or to various chemical treatments thus, for example, it may be treated with sulfur for the preparation of wood preservatives, fungicides and insecticides. It may also be treated with various inorganic oxides or sulfides; for example those of arsenic, zinc, mercury, etc. for the same purposes. 45

45 By the present process the cycle stock is separated into a raffinate which shows improved characteristics for certain uses such as, for example, Diesel oil and an extract which again is a more appropriate raw material for certain other uses than the untreated cycle stock. To illustrate the point the extract is a better raw material for treatment with sulfur than saturated hydrocarbons, because the latter produce a large amount of H₂S in their reaction with sulfur. The extract is also an excellent raw ma- 50

terial for destructive hydrogenation carried out in the presence of a catalyst and in a vapor phase at temperatures between 950-1050° F. whereby a naphtha having excellent solvent qualities is obtained.

5 The following examples are given to illustrate the above:

1. A paraffinic gas oil is cracked, the products being gasoline, fuel oil, gas and cycle stock. The first three are withdrawn from the unit, the cycle stock is subjected to solvent extraction with a mixture of phenol and glycol and separated into raffinate and extract. The raffinate is suitable for cracking with a relatively high gasoline yield and is therefore mixed with fresh feed and returned to the cracking process. The extract is suitable for the production of high octane blending stock and is cracked at high temperature in the separate cracking circuit 20 32-33, the distillate from which latter cracking may be blended with the primary cracking products or may be segregated for use as blending stock to improve the octane number of other distillates.

25 2. The paraffinic gas oil may be cracked and separated into raffinate as in Example 1, the raffinate being returned with fresh feed to the cracking process. The extract being more reactive chemically than either the fresh feed or the raffinate is submitted to sulfurization or arsenication.

30 3. The paraffinic gas oil is cracked and the raffinate is returned to cracking as above. The extract is a low aniline point stock and is suitable for destructive hydrogenation. If hydrogenated at comparatively low temperatures, say below 900° F., it will yield from 30 to 40% of gasoline and 90 to 80% of excellent gas oil, cracking stock or high grade Diesel fuel. If subjected to destructive hydrogenation in the presence of a catalyst at a temperature of say between 950 and 1050° F., it will yield solvents and toxic oils, the former suitable for the preparation of varnishes and the latter for use as wood preservatives, disinfectants and as raw materials for the manufacture of explosives and dyes.

35 The following specific example will illustrate my invention: 18,750 gallons per hour of 30° A. P. I. gas oil (completely miscible with aniline at 175-185° F.) fresh feed are passed into the accumulator 5, after being preheated in 2, 3 and 4 to about 500° F. The mixed feed is pumped from the accumulator at a temperature of about 440° F. and after being preheated in the high pressure heat exchanger 6 to about 540° F., it is 50 passed through the heating coil 7 at the rate of 25,000 gallons per hour and then through the vertical soaking drum 8 in downward direction. The cracking stock is heated in the coil to a 55 temperature between 900 and 930° F. and a pressure of between 250 and 1,000 pounds per square inch is maintained on the soaking drum. The separator is under a pressure of 100-150 pounds per square inch with a bottoms temperature of between 700 and 825° F. The amount of tar removed through cooler 10 is about 2800 gallons per hour. The bubble tower 11 is under a pressure of 95 to 145 pounds per square inch, the temperature at its top between 400-450° F. and at its bottom between 630-680° F. The distillate 60

obtained is approximately 6,550 gallons per hour. 3150 gallons per hour of gas are obtained from which 1315 gallons of gasoline and 1835 gallons per hour of stripped fuel gas are produced. The cycle stock is submitted to a selective solvent treatment (with phenol) as a result of which there is obtained after the removal of the selective solvent, 6250 gallons per hour of raffinate and an equal amount of extract. The raffinate is returned to cracking in the circuit 7 and 8. 65

10 The extract is subjected to hydrogenation in the presence of a sulfactive catalyst at a temperature of 750-850° F. and a pressure of 3000-3500 pounds per square inch. There are obtained 7000 gallons per hour of overhead product 15 separable by distillation into 4500 gallons per hour of 400° F. endpoint gasoline and 2500 gallons per hour of an excellent grade of water white distillate of 38°-40° A. P. I. gravity and above the boiling range of gasoline. The gasoline obtained is of 56-60 octane number by the Co-operative Fuel Research Motor Method and highly susceptible to improvement of octane number by the addition of tetraethyl lead. Alternatively the extract may be subjected to sulfurization or other 20 chemical treatment.

25 My process may be modified in various ways. Thus, for example, different solvents may be used according to the miscibility of the fresh feed with aniline. In the foregoing specific example 30 the cycle stock subjected to extraction with phenol is such that separation of the raffinate and the phenol-extract mixture takes place at a temperature above the freezing point of phenol. If the fresh feed is miscible with aniline at a 35 relatively low temperature and the cycle stock subjected to extraction is completely miscible with phenol at the freezing point of the phenol, then a solvent of lower freezing point such as aniline may be used. By the addition of a second storage tank similar to storage tank 20, either of the two solvents may be employed according to the character of the cycle stock to be subjected to extraction.

40 Many other changes and modifications of my process will be apparent to those skilled in the art and the same is not to be limited by the specific example given for illustration but only by the following claim in which it is my intention to claim all novelty inherent in the invention. 45

50 What I claim is:

55 The process of converting a gas oil into hydrocarbons boiling within the gasoline range which comprises subjecting the gas oil to cracking under conditions suitable for the production of a mixed product containing gasoline and cycle oil, extracting the cycle oil with a selective solvent for aromatic hydrocarbons whereby a raffinate and an extract are obtained, combining the raffinate with the initial gas oil to be cracked, subjecting the extract to cracking at a higher temperature than that maintained in the first cracking step to produce a gasoline of high octane number and higher boiling hydrocarbons, and merging the products of cracking from the second-mentioned cracking step with the products of cracking from the first-mentioned cracking step. 60
